UNITED STATES PATENT OFFICE.

WILLIAM F. MARTIN, OF HARRISBURG, PENNSYLVANIA.

COAL SCREENING AND WASHING MACHINE.

Application filed May 18, 1922. Serial No. 561,979.

To all whom it may concern:

Be it known that I, WILLIAM F. MARTIN, a citizen of the United States, residing at Harrisburg, in the county of Dauphin and State of Pennsylvania, have invented certain new and useful Improvements in Coal Screening and Washing Machines; and I do declare the following to be a full, clear, and exact description of the invention, such as will enable others skilled in the art to which it appertains to make and use the same.

My invention relates to improvements in machines for washing and screening coal, ore and the like and has reference more particularly to machines of this character in which the waste material is washed by water through the screen into a plurality of collecting pockets beneath the latter. Such a machine is shown in my U. S. Patent No. 1412291 issued April 11th, 1922, but the object of the present invention is to improve upon the construction of the patented machine, by providing novel means for agitating the water and waste material in the pockets, so as to prevent the latter from clogging as they were prone to do in the patented machine when screening certain kinds of material.

In carrying out the above end, a further object is to provide a water wheel for operating the agitators, said water wheel being driven by the water discharged through the screen with the waste material.

With the foregoing in view, the invention resides in the novel subject matter hereinafter described and claimed, the description being supplemented by the accompanying drawings.

Figure 1 is a side elevation of the improved machine.

Figure 2 is a longitudinal sectional view.

Figure 3 is a top plan view.

Figure 4 is a transverse sectional view as indicated by line 4—4 of Fig. 2.

Figure 5 is a longitudinal sectional view showing a different form of construction.

Figure 6 is a transverse section on line 6—6 of Fig. 5.

Figures 7 and 8 are detail sectional views showing further modifications.

In describing my invention, I first refer to the construction shown in Figs. 1 to 4. In these views, the numeral 1 designates an appropriate frame which is preferably inclined as shown, a suitable screen 2 being

secured in the upper portion of said frame in any suitable manner, while a plurality of pockets 3 are disposed under said screen to receive the waste material washed through the screen 2. In the present showing, the pockets 3 are of substantially V-shape in section and each pocket is provided with a movable side 4 which is preferably mounted pivotally as indicated at 5, the several movable sides being suitably connected by a connecting rod 6 which is linked at 7 to an eccentric 8 on a transverse rock shaft 9 mounted at one end of the frame. This rock shaft is provided with a suitable operating lever 10 and any preferred means 11 may be employed for holding said lever normally against movement, with the pockets preferably open slightly as shown in Fig. 2.

Positioned within the pockets 3, are a number of vertically movable oscillating agitators 12 carried respectively by rock shafts 13 extending across the frame 1. In the preferred form of construction, each rock shaft 13 is provided with a depending crank arm 14 at the exterior of the frame 1 and the several crank arms are connected by a longitudinal connecting rod 15, the latter being pivoted at 16 to a lever 17 which at 18, is fulcrumed to one side of said frame 1. Suitably pivoted to the lever 17, preferably by means of a bolt 19 which may be passed through any one of a number of openings 20 in said lever, is a connecting rod 21 or pitman which is preferably adjustable in length, by means of a turn-buckle or the like 22. The pitman 21 is connected with an eccentric 23 on the shaft 24 of a water wheel 25, the latter being positioned under the discharge spout 26 which declines from 95 the short bottom 27 with which frame 1 is provided, adjacent its upper end. By this association of parts, the water flowing through the screen 2 onto the bottom 27, will discharge from the latter through the 100 spout 26, thereby rotating the water wheel 25, the result being that the eccentric 23 causes stroking of the pitman 21 and consequent oscillation of the lever 17. This lever in turn reciprocates the connecting rod 15 so that the several shafts 13 are rocked to and fro through the instrumentality of the crank arms 14, thereby causing vertical oscillation of the agitators 12. This agitation effectively prevents accumulation of waste 110 material in the pockets 3 and if the lever 10 is adjusted in a manner to partially open

- the movable sides 4 of said pockets, this waste material will continually wash out under the action of the agitators. It will be understood that the pockets may remain 5 entirely closed if desired and that they may be opened whenever the contents thereof are to be dumped. In all instances, however, clogging of the pockets will be prevented by the continually moving agitators 12.
- 10 While it is preferred to operate these agitators from a water wheel such as 25, so that additional expense for power is unnecessary, it will be understood that the invention is not restricted to this manner of operation.
- 15 Furthermore, while the sides of the pockets are shown straight, it will be understood that this detail is not essential and that said sides may be positioned at any desired angle.
- In the form of construction shown in Figs. 20 5 and 6, the numeral 1^a designates the carrying frame and 2^a has reference to the screen. In this form of the invention, the collecting pockets 3^a are of substantially semi-cylindrical form and may well be constructed of 25 sheet metal as shown, each pocket being provided with a movable side 4^a pivotally mounted as indicated at 5^a. A connecting rod 6^a operated in the same manner as the connecting rod 6 is pivoted to the movable sides 4^a and may be set so that a slight gap 30 may be left at the bottom of each pocket if desired, or the bottoms of the pockets may be entirely closed and the movable sides swung outwardly only at suitable intervals for dumping their contents. In all instances, however, clogging of the pockets is prevented by suitable agitators, each of which preferably comprises a rock shaft 13^a, a pair of arms 30 extending rigidly from said rock shaft, an 35 arcuate plate 31 extending between and secured to said arms 30, and an upstanding wall 32 also extending between the arms 30 and resting at its lower edge upon the plate 31. The several rock shafts 13^a are adapted 40 to be operated in any suitable manner, but the same construction as that above described for operating the shafts 13 is preferably used. The result is that as the shafts 13 are oscillated, the agitators continually 45 sweep across the curved pockets or walls and thereby effectively agitate the waste material and water therein so that it will readily wash out as soon as the pockets are opened sufficiently.
- 50 In the construction shown in Fig. 7, the numerals 32^a designate agitators of the same construction as those described in the preceding paragraph, although other structures might well be used. The shape of the 55 pockets 3^b however is changed as each pocket is provided with a pair of straight downwardly converging side walls 33 and with an arcuate bottom 34 whose edges are spaced 60 from the lower edges of the side walls 33 to 65 provide outlet gaps 35 for the waste material

and water. The walls 33 and 34 are rigidly secured to the sides of the frame 1^b under the screen 2^b and it will be seen that in this form of the invention, when the agitators 32^a are oscillated by any suitable means such as that above described, the waste material and water will be alternately moved toward opposite sides of the pockets so that a discharge takes place first through one of the gaps 35 of each pocket and then through the other, 75 but in no case can the waste material lodge in said pockets, due to the effective agitation thereof.

In the construction shown in Fig. 8, the construction is approximately the same as that shown in Fig. 7, with the exception however that the side walls 33^a, as well as the bottom wall 34^a are curved concentrically with the axis of the agitator 32^a.

By providing a construction such as that herein disclosed, it will be seen that I have greatly improved upon the patented device and while the details which I have shown, are preferably followed, it is to be understood that within the scope of the invention 90 as claimed, numerous minor changes may be made.

I claim:

1. A screening machine comprising a frame, a screen therein, a plurality of collecting pockets beneath said screen and having a discharge opening, rock shafts positioned in said pockets respectively, agitators carried by said rock shafts and having movement towards and away from the discharge 100 opening when in motion, and means for simultaneously oscillating all of said rock shafts.

2. A screening machine comprising a frame, a screen therein, a plurality of collecting pockets beneath said screen and each having an outlet, rock shafts extending across the frame and positioned in said pockets respectively, agitators carried by said rock shafts and having movement 110 towards and away from the outlet when in motion, crank arms extending in the same direction from said rock shafts and positioned at the exterior of the frame, a longitudinal connecting rod pivoted to all of said 115 crank arms, and means for reciprocating said connecting rod to produce oscillation of said agitators.

3. A screening machine comprising a frame, a screen therein, a plurality of collecting pockets in the frame beneath said screen, agitators in said pockets, a water wheel associated with said frame and driven by water supplied to the latter, and operating connections between said water wheel 125 and agitators for operating the latter from the former.

4. A screening machine comprising a frame, a screen therein, a plurality of collecting pockets in the frame beneath said 130

screen, agitators in said pockets having rock shafts extending to the exterior of the frame, crank arms secured to the rock shafts and extending in the same direction therefrom, 5 a longitudinal connecting rod pivoted to all of said crank arms, a water wheel associated with the frame and driven by water supplied to the latter, and operating connections between said water wheel and the 10 connecting rod for producing reciprocation of the latter.

5. A screening machine comprising a frame, a screen therein, collecting pockets in the frame beneath said screen, agitators in 15 said pockets having rock shafts extending to the exterior of the frame, crank arms on the rock shafts extending in the same direction therefrom, a longitudinal connecting rod pivoted to all of said crank arms, a lever

fulcrumed to the frame and pivotally connected with said connecting rod, a pitman pivoted to and extending from said lever, and a water wheel having an eccentric connected with said pitman, said water wheel being positioned to be operated by water 25 supplied to the screening machine.

6. A screening machine comprising a frame, a screen therein, pockets in the frame beneath said screen, a bottom for the frame located beneath certain of said pockets, a 30 water wheel positioned to be operated by water running from the end of said bottom, and agitators in said pockets operated by means of said water wheel.

In testimony whereof I have hereunto set 35 my hand.

WILLIAM F. MARTIN.
